UNITED STATES PATENT OFFICE

WILLIAM T. FELTON, OF BUFFALO, NEW YORK

WARNING SIGNAL

Application filed October 9, 1929. Serial No. 398,305.

My invention relates to a device adapted to perform a waving or wig-wag motion when exposed to the wind, and is intended primarily for use as a danger signal warning traffic to stop or at least proceed with caution, as in the case of roads under construction, streets torn up for the laying of pipes or repairs, and in other situations where danger exists to traffic or to men working on or below streets or roads. The object of my invention is to provide a device of this character which will have a much greater motion than the danger flags now in common use, and which thereby will more readily attract the attention of drivers and thus be more effective for its purposes.

A satisfactory and preferred embodiment of my invention is illustrated by the accompanying drawings, in which Fig. 1 is an elevation of my improved signal, with parts in section; Fig. 2 is a top view of the base of the device; Fig. 3 is a detail vertical section of a portion of the signal, on an enlarged scale; and Fig. 4 is a bottom view of an expansion plug employed in said embodiment.

At A I have shown a base, of cast iron or other heavy material. This base is preferably of hemispherical shape with a bottom recess A' to form an annular ridge or ledge A'' to give the base a firmer footing on uneven ground. At the top, the base has a central upward projection A² made with a downwardly flaring recess or socket A³. The upper end of such socket is of sufficient diameter to slip into it the lower end of a coiled spring B, which lower end is originally of the same diameter as the main portion or body of the spring. To secure the spring in the socket A³, I prefer to employ the expanding device illustrated, which comprises a wedge C, shown as of conical shape, located within the socket and preferably cast integral with the base. The wedge is of smaller diameter than the inside of the spring B.

This spring is then inserted into the socket A³, the lower end of the spring touching the bottom of the socket and surrounding the wedge. I then drop into the spring, through its open upper end, a plug D of cylindrical

shape, having two vertical cuts or slits D' at right angles to each other, extending from the bottom of the plug to within a short distance from its upper end. The upper end or point of the wedge will engage the plug D at the intersection of the two slits D'. A rod is then inserted into the spring from above, and while the lower end of such rod engages the upper end of the plug D, blows are directed upon the upper end of the rod by means of a hammer or other suitable tool. The plug D is thus gradually forced from the original position shown in Fig. 3 by dotted lines, downwardly until it engages the bottom of the socket A³. During such downward movement, the split portion of the plug is spread or expanded by the action of the wedge C, and this in turn causes the lower end of the spring B to be expanded within the flaring socket, as shown, with the result that the spring is firmly secured or anchored in said socket, a rigid connection being thus established between the base A and the lower end of the spring.

The upper portion of the spring B receives the lower end of a staff E, of wood or other suitable material, to the upper end of which is secured the signal proper F, generally a flag of red cloth, which if desired, may be provided with a spreader wire F' to assist in keeping it in an open position so that it will catch the breeze more readily. Near the lower end of the staff E, I provide a transverse hole E' adapted to receive a pin G the ends of which project between adjacent convolutions or turns of the coiled spring. Preferably, the pin G is removable, an ordinary cotter pin being generally employed. The hole E' and the pin G are preferably not at right angles to the longitudinal axis of the staff E, but oblique, being inclined relatively to said axis at an angle corresponding to the pitch of the spring coils. Thus, if the flag staff E is rotated about its longitudinal axis, the pin G will move or screw up or down along the coils of the spring B, bringing the lower end of the staff farther from, or nearer to, the socket A³, for a purpose to be explained presently. In order to prevent accidental separation of the staff from the

spring, which might occur if the staff were rotated until the pin G would unscrew from the upper end of the spring, I prefer to fasten the uppermost turn or coil of the spring to the 5 adjacent turn, for instance by spot-welding, as indicated at B'.

When the base A is set on the ground, even if such ground is perfectly level, the unbalanced condition of the flag and staff structure (since the flag is to one side of the staff) will cause the spring B and staff E to lean to one side, as the center of gravity of the flag and staff structure is not upon the longitudinal axis of the spring B, but lies to 10 one side of said axis, and since the weight of such structure is sufficient to overcome the tension of the spring and bend such spring laterally. The flag will thus be caused to hang in a position in which it will readily 15 catch even a light breeze. As the wind generally comes in puffs, the flag and staff will bend to and fro, or wig-wag, thus attracting attention much more effectively than when the staff remains stationary. Should the direction of the wind change, even but slightly, 20 this will cause the staff to sway to different directions, the spring B allowing movement of the staff to different inclinations, in all directions. When only a light wind is blowing, the staff will be adjusted to a position 25 in which the pin G is near the outer end of the spring B, so that the mobility of the spring and of the staff will be at a maximum. If the wind is very strong, the staff E will 30 be rotated to bring the pin G nearer to the base A, so that a relatively long portion of the staff will be within the spring B. It will be obvious that only the free portion of the spring, that is to say, the portion into which 35 the staff E does not project, is able to bend or sway, while that portion of the spring which surrounds the staff is held against lateral bending and is therefore practically inactive. Thus, by rotating the staff in one 40 direction or the other, I can adjust the length of the free or active portion of the spring, and thus adjust the spring to a condition of greater or less effective stiffness, as may be 45 desirable in view of wind conditions.

50 While I have described a specific embodiment of my invention in which the base is adapted to be set on the surface of a road or street, it will be understood that other forms of base might be employed, depending on the particular use for which the device, 55 may be intended. Furthermore, while my invention has been directed primarily to the production of a danger signal, it will be obvious that the structure (such as the flag and staff) which waves or sways in the wind 60 may be used for other purposes, wherever it is desired to produce an effect which will attract the attention of beholders.

65 Various modifications may be made with-

out departing from the nature of my invention as set forth in the appended claims.

I claim:

1. An article of the character described, comprising a base, a spring attached to the base, and an attention-attracting device connected with said spring and having its center of gravity to one side of the center of gravity of the spring, said device being of a weight sufficient to overcome the tension of the spring and cause such spring to be normally bent to one side. 70

2. An article of the character described, comprising a base, a coiled spring one end of which is attached to said base, an attention-attracting device provided with a staff projecting into said spring and rotatable therein, and a projection extending from said staff between the convolutions of the coil to cause such staff to move toward or from 75 the base of the staff is rotated. 80

3. An article according to claim 2, in which the projection extending between the convolutions of the spring is disposed obliquely to the staff, at an angle corresponding to the 85 pitch of the spring coils. 90

4. An article according to claim 2, in which the spring coils are closed at the outer end of the spring, to prevent the projection on the staff from accidentally working out from 95 between the coils of the spring. 100

In testimony whereof I have hereunto set my hand.

WILLIAM T. FELTON.
